UNITED STATES PATENT OFFICE.

ARTHUR F. MILBRATH, OF MILWAUKEE, WISCONSIN, ASSIGNOR TO WISCONSIN MOTOR MANUFACTURING COMPANY, A CORPORATION OF WISCONSIN.

MAGNETO-COUPING.

1,195,259.

Specification of Letters Patent. Patented Aug. 22, 1916.

Application filed August 7, 1915. Serial No. 44,317.

To all whom it may concern:

Be it known that I, ARTHUR F. MILBRATH, a citizen of the United States, residing at Milwaukee, in the county of Milwaukee and State of Wisconsin, have invented certain new and useful Improvements in Magneto-Couplings, of which the following is a specification, reference being had to the accompanying drawing, forming a part thereof.

10 This invention relates to an adjustable magneto coupling, and the objects of the invention are to provide a simple, conveniently adjustable and accurate coupling device for connecting a magneto with a driving shaft 15 through which power is transmitted to the magneto.

Referring to the drawings which accompany this specification and form a part hereof, which drawings illustrate an embodiment of this invention, and on which drawings the same reference characters are used to designate the same parts wherever they may appear in each of the several views, Figure 1. is a front elevation of the coupling; 20 Fig. 2. is a side elevation of the coupling; Fig. 3. is a section through the coupling on the line *a—a* on Fig. 1., looking in the direction indicated by the arrows; Fig. 4. is an enlarged elevation of one of the clutch members.

Referring to the drawings, the reference numeral 1 designates a magneto, which is provided with the shaft 2, and the reference numeral 3 designates a driving shaft which 35 is coupled with the shaft 2 of the magneto by the coupling to be hereinafter described. The shaft 3 is rotated from a rotating part of the engine in any convenient or suitable manner, as will be readily understood. A 40 yoke member 4 is secured to shaft 2 of the magneto and consists of a hub member provided with arms extending therefrom on opposite sides thereof and in line with each other. The yoke member 4 is secured to a 45 leather disk 7 by two bolts 5 and 6. The leather disk 7 is provided with a central aperture 8 for a nut (not shown) which retains the yoke 4 on the magneto shaft 2. Clutch members 9 and 10 are provided with 50 screw bolts 11 and 12, or other suitable fastening means for holding the clutch members in engagement with a circumferentially toothed member as for example the ordinary gear to be hereinafter described.

Each of the clutch members 9 and 10 is 55 provided with a projecting lug, which are designated by the reference numerals 13 and 14, respectively, and these lugs are secured to the leather disk 7 by bolts 15 and 16, which engage with the leather disk 7 in a line substantially at right angles with a line through the bolts 5 and 6. The leather disk which forms the power transmitting connection between the clutch members 9 and 10 and the yoke member 4 permits movements of the 60 clutch members 9 and 10 with respect to the yoke member 4, the construction described forming a flexible coupling between the shafts 2 and 3. The opposing faces of the clutch members 9 and 10 are provided with 65 substantially semi-cylindrical recesses provided with teeth 18 and 19 which are adapted to project into the spaces between the teeth on the circumferentially toothed member 17, which is provided on the shaft 3. 70

It is preferred to provide a plurality of teeth on the clutch members 9 and 10 to secure strength and to admit of fine adjustment. The teeth on the circumferentially toothed member 17 are preferably ordinary 80 gear teeth and the intermediate teeth on the clutch members 9 and 10 are preferably ordinary gear teeth to mesh with the teeth on the circumferentially toothed member 17 but the end teeth on each of the clutch members 9 85 and 10 are so formed that the teeth on the clutch members can be inserted into the spaces between the teeth on the circumferentially toothed member 17, or withdrawn from the said spaces, by radial movements with 90 respect to the circumferentially toothed member 17, as will be readily understood from an inspection of Figs. 1. and 4. of the drawings. By forming the end teeth on the clutch members 9 and 10, as described, more 95 teeth can be provided on the clutch members to engage with the circumferentially toothed member 17 than would otherwise be possible/ while retaining the desirable feature of engaging the clutch teeth with the circumferentially toothed member, or disengaging them therefrom, by radial movements of the clutch members with respect to the circumferentially toothed member 17.

The construction described provides a 105 flexible connection between the driving shaft 3 and the magneto shaft 2 and enables the shaft 2 of the magneto to be so set with re-

spect to the driving shaft 3 that the ignition spark or sparks will be timed correctly for the proper performance of the engine. An adjustment is effected by loosening the 5 screws 11 and 12 so that the teeth on the clutch members can be withdrawn from the spaces between the teeth on the circumferentially toothed member 17, and the clutch members, together with the leather disk 7, 10 the yoke member 4 and the magneto shaft 2 can be rotated with respect to the circumferentially toothed member 17 in either direction until the proper position is reached for the correct relation between the magneto 15 and the movable parts of the engine.

The leather disk 7, if of sufficient size, will be flexible enough so that the teeth on the clutch members can be disengaged from the space between the teeth on the circumferentially toothed member 17, but, if the 20 leather disk 7 should be so small that its flexibility would not permit the teeth on the clutch members to be disengaged from between the teeth on the circumferentially toothed member 17 by bending the leather disk 7, the bolts 15 and 16 can be readily removed, thereby permitting the clutch members 9 and 10 to be disengaged from the circumferentially toothed member 17, and then 25 the leather disk 7, the yoke member 4 and the magneto shaft 2 can be turned in either direction, as hereinbefore explained, until the proper position is reached for the correct relation between the magneto and the 30 movable parts of the engine. The clutch members can then be secured to the leather disk by the bolts 15 and 16 and clamped 35

upon the circumferentially toothed member 17 by the screw bolts 11 and 12.

What is claimed is:

1. An adjustable magneto coupling comprising in combination a leather disk, a yoke member secured thereto, clutch members secured to each other and secured to said leather disk in a line at substantially right angles with said yoke member, a driving shaft provided with a circumferentially toothed member, the clutch members being provided with teeth adapted to engage with said circumferentially toothed member and being separable from each other radially of said circumferentially toothed member. 40 45 50

2. An adjustable magneto coupling comprising in combination a leather disk, a yoke member secured thereto, clutch members secured to said leather disk in a line at substantially right angles to said yoke member, a driving shaft provided with a circumferentially toothed member, said clutch members being each provided with a plurality of teeth adapted to engage within the spaces between the teeth on said circumferentially toothed member, the teeth on each clutch member being so shaped that the clutch members can be engaged with the circumferentially toothed member or disengaged therefrom by radial movements with respect thereto. 55 60 65

In witness whereof I hereto affix my signature in presence of two witnesses.

ARTHUR F. MILBRATH.
